SALES BOOK

George F. Washburne, New York, N. Y., assignor
to The Egry Register Company, Dayton, Ohio,
a corporation of Ohio

Application September 28, 1942, Serial No. 459,929

8 Claims. (Cl. 282—22)

This invention relates to a sales record book of the type wherein an original and duplicate copy is produced, the original being removed from the sales book while the copy is retained in the same. Also, a customer's receipt is provided and is produced at the same time the original copy is made.

An object of the invention is to provide a sales record book wherein a single sheet of carbon is permanently secured within the book and the record sheets are arranged to be placed on opposite sides of the carbon without removing the carbon from its fixed position in the book.

Another object of the invention is to provide a sales record book wherein a sheet of carbon is permanently attached therein and the record sheets are arranged within the book so that they can be brought into engagement with opposite sides of the carbon without handling the carbon sheet.

Another object of the invention is to provide a sales record book wherein a sheet of carbon is permanently secured midway between the top and bottom of the depth of the sheets in the book and the sheets are constructed and arranged in a manner that they can be removed from the book individually without interfering with the fastening arrangement of the carbon sheet so that the carbon sheet always remains in position midway between the top and bottom of the book with respect to its depth.

Another object of the invention is to provide a sales record book having a plurality of record sheets that are folded as a pack to produce a fold line over which all of the sheets are folded, and wherein a carbon sheet is disposed within the pack midway between the top and bottom thereof in a permanent arrangement with respect to the pack so that individual sheets can be removed from the pack beginning with the center sheet and working toward the outer leaves whereby the lower half of the pack produces carbon copies while the upper half of the pack produces original copies.

It is another object of the invention to provide a sales record book constructed and arranged in accordance with the foregoing object wherein the carbon copies are permanently secured within the book and may be stowed beneath the book.

It is another object of the invention to provide a sales record sheet having an original form, a carbon copy form and a customer's receipt form provided on a single paper sheet.

It is another object of the invention to provide a sales record book that is constructed and arranged in a manner that the record sheets can be removed from the book and fresh record sheets placed adjacent opposite sides of the carbon sheet without handling the carbon sheet.

Further objects and advantages will become

apparent from the drawing and the following description.

Figure 1 is a plan elevational view of a record book constructed in accordance with this invention having corner portions thereof broken away to show the various layers provided in the book.

Figure 2 is an enlarged longitudinal cross sectional view of the record book taken along line 2—2 of Figure 1.

Figure 3 is a perspective elevational view of the record book arranged for use when placing data upon the record sheets.

Figure 4 is a perspective elevational view similar to Figure 3 but showing the first operation in removing the original copy of the record sheets from the book.

Figure 5 is a perspective elevational view similar to Figures 3 and 4 but showing the original copy of the record sheet removed from the sales book and the manner in which the carbon copy is folded beneath the book for storing the same.

Figure 6 is a perspective elevational view of the original copy of the record sheet removed from the book as shown in Figure 5, and showing the manner in which a customer's receipt or stub is removed from the original copy, the stub being a carbon copy of the data on the original.

In this invention the sales record book is constructed and arranged in a manner that the record sheets are arranged in book form by folding a stack of the sheets transversely along a fold line so that they all fold over one another along a common fold line, and therefore produce a book that has an upper section and a lower section. A carbon sheet is disposed between the two sections of the book and is adapted to be permanently secured therein so that the record sheets can be removed from the book and fresh sheets placed adjacent opposite sides of the carbon sheet without handling the carbon sheet.

As shown in Figures 1 and 2, the book is arranged in completely assembled condition, the book 10 consisting of an upper section 11 and a lower section 12. The upper and lower sections 11 and 12 consist of single sheets of paper that are arranged in pack form and are folded along a fold line 13, whereby the upper section 11 is folded upon the lower section 12 along a common fold line so that the book is arranged in upper and lower portions.

Each of the sheets 15 of the book 10 consists of an upper portion 11a and a lower portion 12a. Considering the portion 12a as the face portion of the sheet, the portion 11a has the form printed thereon on the rear face of the sheet so that when the portion 11a is folded along the line 13a upon the portion 12a, it will be arranged with the reverse face toward the person using the book so that the original data can be placed thereon. The sheets 15 are provided with a perforation

16 which forms the fold line 13a, and are provided with a second perforation 17 that is spaced from the first perforation 16 so that the portion of the sheet 15 between the perforations 16 and 17 provides a stub 18 that can be removed from the original copy sheet 11a and the carbon copy sheet 12a. When the sheets are used in a sales book this stub 18 may form the customer's receipt.

The sheets 15 are also provided with holes 19 through which staples are driven to secure the lower section 12 to a stiff back member 20.

As previously mentioned, the individual sheets are printed so that the portion 11a of each of the sheets has the data form upon the reverse face of the sheet and the portion 12a has the data portion upon the front face of the sheet. When the book is used as a sales record book the stub 18 is printed with the same form as appears upon the upper end of the portion 11a of the sheet 15 so that the same information would appear upon the stub 18 as appears upon the upper end of the original copy form 11a.

To assemble the book, a plurality of the sheets is arranged in a flat stack so that the perforation lines 16 and 17 are in vertical alignment with one another. A carbon sheet 25 is placed upon the uppermost sheet of the stack to cover the portion 12a of the sheets. This single carbon sheet 25 extends above the perforation line 17 to cover a portion of the stub 18, and extends below the perforation line 17 to cover the portion 12a of the sheet. With the carbon sheet 25 in place upon the portion 12a, as shown in Figure 1, the stack of sheets is placed upon the stiff back 20 and staples 21 are driven through the carbon sheet and the lower section 12 into the stiff back 20 to retain the section 12 upon the stiff back, and retain the carbon sheet upon the uppermost sheet of the section 12. The staples 21 are driven through the perforation line 17 so that the sheets can be removed from the book in a manner that will be hereinafter described.

The section 12 is then folded around the lower end 22 of the back 20, as shown in Figure 2, so that the lower ends of the sheets comprising the section 12 will be folded against the rear side of the back 20. Staples 23 are then driven through the back 20 and through the folded ends 24 of the section 12 so that the lower portions of the sheets 15 comprising the section 12 will be permanently secured to the back 20. The portions 11a of the sheets 15 comprising the section 11 are then folded along the perforation line 16 so that the section 11 lies upon the carbon sheet 25.

When data are to be placed in the book, the sheets comprising the upper section 11 are moved rearwardly with the exception of the lowermost sheet of this section, which would be the center sheet, as shown in Figure 3. This center sheet is adjacent the carbon sheet 25. Data can then be placed on the portion 11a of the sheet 15 including the upper end or head portion of the sheet 15 corresponding to the stub 18 on the rear portion or carbon sheet portion 12a. To remove the original copy form 11a from the book the operator will grasp the upper lefthand corner of the sheet 15 adjacent the perforation line 16, a thumb grasp marker 26 being provided to direct the operator to the proper corner of the sheet, suitable directions being provided with the marker 26 if desired. With the upper lefthand corner of the sheet 15 grasped between the thumb and forefinger, the sheet 15 can be moved upwardly

from the book so that the upper portion 11a of the sheet 15 and the stub portion 18 will be removed from the carbon copy portion 12a along the perforation line 17, as shown in Figure 4.

As previously mentioned, the section 12 is stapled to the back through the perforation line 17, and the carbon sheet 25 is retained by staples 21 at the perforation line 17, so that removal of a center sheet from the book along the perforation line 17 will not disturb the carbon sheet 25 nor the carbon copy 12a.

The original form copy 11a with the carbon copy stub 18 is then lifted from the book, as shown in Figure 5, and the carbon copy stub 18 is then removed from the original copy 11a along the perforation line 16, as shown in Figure 6.

To remove the carbon copy 12a from beneath the carbon sheet 25 the operator will place a thumb at the thumb marker 21 provided in the lower righthand corner of the carbon copy sheet 12a, as shown in Figure 1. By pressing upon the thumb marker 21 in a downward direction the sheet 12a will slide from beneath the carbon sheet 25, as shown in Figure 5, so that it can then be folded beneath the rear side of the back 20 for a permanent record.

With the carbon copy 12a removed from beneath the carbon sheet 25, the book is then in condition for use and producing another record, and it will be noted that it has not been necessary to touch the carbon while removing the data sheets from the book, and that the carbon sheet 25 will be permanently attached to the book at all times and in proper position with respect to the data sheets. The carbon sheet will not be interfered with because the data sheets are separated along the perforation line 17, which is the line upon which the carbon sheets are retained by the staples 21.

While the form of the invention disclosed herein is a preferred form, yet it is to be understood that the arrangement is susceptible of modification without departing from the spirit of the invention, and that all such modifications as fall within the scope of the appended claims are intended to be included herein.

Having thus fully described my invention what I claim as new and desire to secure by Letters Patent is:

1. A book for recording data comprising a plurality of superposed paper sheets having a perforation line extending transversely thereof, said perforations being arranged in planar alignment, said sheets being folded upon a common fold line closely adjacent said perforation line to form a book comprising an upper and a lower book section divided along a mid point by the folding of the sections, a transfer sheet disposed between the sections of the book having portions thereof extending above and below said perforation line, and means extending through the perforation line securing the sheets together and securing the transfer sheet to a book section at the perforation line.

2. A pad for receiving data comprising a plurality of superposed sheets each having a perforation line extending transversely thereof, said perforation lines being arranged in planar alignment, said sheets being folded transversely upon a common fold line adjacent said perforation line to produce an upper and a lower book section divided at a mid point by the fold line, a transfer sheet disposed between said book sections having a portion thereof extending above and below

said perforation line, a stiff back for said pad, and means extending through said transfer sheet and said lower section to secure the same to said back at said perforation line.

3. A sales record book comprising a plurality of superposed paper sheets each having a transverse perforation line, said perforation lines being arranged in planar alignment, said sheets being folded upon a common fold line adjacent said perforation line to produce book sections disposed above and below a plane extending through the fold lines of said sheets, a transfer sheet disposed between said book sections in the plane of said fold lines, and means extending through said transfer sheet and the book section below said plane and at said perforation line to secure said sheets together and secure said transfer sheet to said book section, whereby the sheets can be removed from above and beneath said transfer sheet at the perforation line without disengaging the transfer sheet from the lower book section and without leaving any portion of the sheet between the book sections at the fastening point thereof.

4. A sales record book comprising a plurality of superposed paper sheets each having a transverse perforation line, said perforation lines being arranged in planar alignment, said sheets being folded upon a common fold line to produce book sections disposed above and below a plane extending through the fold lines of said sheets, a transfer sheet disposed between said book sections in the plane of said fold lines, a stiff back for said book, means extending through said transfer sheet and the book section below said plane and at said perforation line to secure said sheets to said back and secure said transfer sheet to said book section, said lower book section having ends thereof folded over the end of said back into engagement with the rear face thereof, and means for securing said ends of said book section to said back.

5. A sales record book comprising a plurality of superposed paper sheets each having a transverse perforation line, said perforation lines being arranged in planar alignment, said sheets being folded upon a common fold line to produce book sections disposed above and below a plane extending through the fold lines of said sheets, a transfer sheet disposed between said book sections in the plane of said fold lines, a stiff back for said book, means extending through said transfer sheet and the book section below said plane and at said perforation line to secure said sheets to said back and secure said transfer sheet to said book section, said lower book section having ends thereof folded over the end of said back into engagement with the rear face thereof, said sheets in said lower book section having openings therein arranged in vertical alignment adjacent the face of said back, and means driven through said back from the face side thereof through said openings to engage said end of said lower section to secure the same to said back.

6. A book for recording data comprising a plurality of superposed paper sheets each having a perforation line extending transversely thereof, said perforation lines being arranged in planar alignment, said sheets each having a second perforation line disposed between said first perforation line and one end of said sheets to form a stub sheet between said perforation lines, a transfer sheet disposed upon the top sheet of said plurality of sheets having a portion thereof ex-

tending between said first and second perforation lines and a portion extending below said first perforation line, and means extending through said transfer sheet and through said paper sheets at said first perforation line to secure said paper sheets together and said transfer sheet upon said paper sheets, said sheets being folded substantially on said second perforation line to dispose the same above said transfer sheet, whereby the sheet above said transfer sheet and said stub sheet can be grasped at said fold line to remove the same from the book at said first perforation line and said sheet below said transfer sheet can be removed from beneath the same without disengaging said transfer sheet from the book and without leaving any portion of the sheets between the remaining folded sheets.

7. A book for recording data comprising a plurality of superposed paper sheets each having a perforation line extending transversely thereof, said perforation lines being arranged in planar alignment, said sheets each having a second perforation line disposed between said first perforation line and the upper end of said sheets, a transfer sheet disposed upon the top sheet of said plurality of sheets having a portion thereof extending between said first and second perforation lines and a portion extending below said first perforation line, a stiff back for said book, means extending through said transfer sheet and through said paper sheets at said first perforation line to secure said paper sheets and said transfer sheet to said back, said sheets being folded substantially upon said second perforation line to position the same above said transfer sheet in the form of an upper book section, said sheets below said transfer sheet forming a lower book section and extending substantially beyond the end of said upper book section, said extending end of said lower book section being folded around the end of said back adjacent the rear face thereof, and means extending through said back and said end of said lower book section to secure the same to said back.

8. A book for recording data comprising a plurality of superposed paper sheets each having a perforation line extending transversely thereof, said perforation lines being arranged in planar alignment, said sheets each having a second perforation line disposed between said first perforation line and the upper end of said sheets, a transfer sheet disposed upon the top sheet of said plurality of sheets having a portion thereof extending between said first and second perforation lines and a portion extending below said first perforation line, a stiff back for said book, means extending through said transfer sheet and through said paper sheets at said first perforation line to secure said paper sheets and said transfer sheet to said back, said sheets being folded substantially upon said second perforation line to position the same above said transfer sheet in the form of an upper book section, said sheets below said transfer sheet forming a lower book section and extending substantially beyond the end of said upper book section, said extending end of said lower book section being folded around the end of said back adjacent the rear face thereof, openings in said lower book section adjacent the end of said back, and means moved through said openings into said back and through said end of said lower book section to secure the same to said back.
